UNITED STATES PATENT OFFICE.

HENRY DE SMITH, OF ROCHESTER, NEW YORK, ASSIGNOR TO M. D. KNOWLTON COMPANY, OF ROCHESTER, NEW YORK, A CORPORATION OF NEW YORK.

FEEDING DEVICE FOR STAY-APPLYING MACHINES.

1,305,343.

Specification of Letters Patent. Patented June 3, 1919.

Application filed August 5, 1916. Serial No. 113,264.

To all whom it may concern:

Be it known that I, HENRY DE SMITH, a citizen of the United States, and resident of Rochester, in the county of Monroe and 5 State of New York, have invented certain new and useful Improvements in Feeding Devices for Stay-Applying Machines, of which the following is a specification.

My invention relates to that class of machines adapted for applying stays or reinforcing strips to the corner joints of boxes made of paperboard or like material, in which are embodied stay-strip applying means and stay-strip feeding means; the 10 said feeding means being operative to feed a stay-strip from a supply roll to said applying means to be operated upon thereby in usual and well known manner.

The feeding means in most common use 15 in this class of machines comprise a reciprocating strip-engaging device and means for operating the same in a manner whereby it will be caused on its forward feeding stroke to engage and carry forward the strip and then become released from said strip at the limit of its forward stroke so as to move backwardly without producing any corresponding backward movement of the strip. Such feeding device comprises a carrier having mounted thereon two co-operating 20 gripping members arranged to permit of the passage of the stay-strip therebetween, one of which members is stationary with respect to the carrier and the other pivoted for movement to and from a gripping position relative to said stationary member. Connected with this movable gripping member is an actuating means which, in the operation of the machine, first rocks said member into gripping engagement with the strip, and then, by a continued movement, imparts 25 a forward stroke to the complete feed device. Such forward stroke of the feed device determines the forward feeding of the stay-strip. To produce accurate feeding, it is obvious that the upper pivoted gripping member should be caused to firmly grip the stay strip before the feed device begins its forward or feeding stroke and to maintain 30 such grip until the completion of said stroke. To accomplish this, means have heretofore been provided for holding the feed carrier in frictional engagement with a braking surface on the stationary guide-plate whereby 35 the feed carrier is held against movement

by its actuating means until the upper gripping member has been moved into firm gripping engagement with the stay strip. Such means, however, has not been provided with an adjustment for varying the friction between the feed carrier and the guide-plate as may be required in providing for the wear of the parts, etc., and this has been the cause of some trouble in maintaining the proper operation of the feed device in this 40 class of machines. It has therefore been the object of my present invention to provide an improved braking means for controlling the movement of the feed carrier on its guide-plate whereby the desired braking action 45 may be readily obtained under all conditions. This object is attained by my invention as hereinafter described and claimed and as illustrated in the accompanying drawings, in which—

Figure 1 is a side elevation of part of a stay-applying machine provided with my invention.

Fig. 2 is an enlarged side elevation of the feed device removed from its connection 50 with the machine and showing the upper gripping member in lowered strip-engaging position.

Fig. 3 is a horizontal section taken on the line 3—3 of Fig. 2.

Fig. 4 is a vertical section taken on the line 4—4 of Fig. 2.

Fig. 5 is a horizontal section through a feed device embodying a modified form of my invention, and its supporting guide-plate, the section being taken on a line corresponding to that of Fig. 3, and

Figs. 6 and 7 are detail views of parts of the device shown in Fig. 5, to be hereinafter referred to.

Similar reference characters indicate like parts in the several figures of the drawings.

The machine here shown as provided with my invention is a "stayer" of well known construction and operation, and therefore 80 will be only briefly described herein.

The several parts constituting the machine are mounted upon a suitable supporting frame, indicated generally by the reference numeral 2. In the upper part of this frame 85 is journaled a drive shaft 3 having at its rear end a clutch-controlled drive pulley 4.

At the front end of the machine is the stay-applying means, comprising two co-operating presser dies, the lower of which, 90

indicated at 5, is normally stationary and adapted to support a box-corner, while the upper one, indicated at 6, is vertically movable and adapted to press a stay-strip upon 5 the box-corner on said lower die. The movable die 6 is mounted in a reciprocating head 7 which is actuated from a crank-pin on the drive shaft 3 through the medium of a pitman 8, in usual manner.

10 In the operation of the machine, the stay-strip, indicated at 8, is adapted to be fed from a supply reel (not shown) to a position between said presser dies, by a suitable feed device. This feed device comprises a 15 reciprocatory carrier plate 9 slidably connected with a stationary guide plate 10 and having connected therewith two coöperating gripping members, one of which, indicated at 11, is fixed with respect to the plate 9 and 20 arranged to engage with the stay strip at the under side thereof, and the other, indicated at 12, is pivoted to the plate 9 and arranged to engage with the stay-strip at the upper side thereof. With this construction of feed 25 device, the movable or pivoted member 12 should be caused to coöperate with the lower member 11 to engage and carry forward the strip upon the forward stroke of the device, and to release the strip at the limit of said 30 forward stroke and maintain such release during the return stroke of the device. Such operation of the feed device is effected in the present case by means of an actuating lever 13, pivoted at its upper end to the 35 frame at 14, and at its lower end connected through a link 15 with a lever arm 16 of the pivoted member 12. The lever 13 is given its forward throw by a cam 17 on the shaft 2 engaging a roll 18 thereon, and is given its 40 return throw by a connecting spring 19. Upon the forward throw of the lever 13, the member 12 is first caused to rock downward into gripping engagement with the strip lying over the lower member, as shown in 45 Fig. 2, after which, the continued movement of the lever effects an advance of the feed device—comprising the carrier 9 and supported members—and engaged strip. After the lever has swung forward a predetermined 50 distance, it is then retracted, thereby operating to first raise the member 12 to strip-releasing position by rocking its arm 16 into contact with a stop projection 20 on the carrier plate 9, as shown in Fig. 1, and 55 then returning the feed device to its starting position.

The machine as thus far described is of usual construction and operation and does not require a more detailed description for 60 the proper understanding of my present invention.

The carrier 9 as here shown is provided at its rear side with a supporting and guiding rib 21 which is fitted to slide within an 65 open elongated slot 22 in the guide-plate 10.

As a means for retarding the carrier 9 against feeding movement until its gripping jaw or member 12 has been moved into strip-engaging position, it is held in frictional engagement with one side of the guide-plate 70 10 by means of a sliding shoe 23 at the opposite side of said guide-plate, with which it is connected by a bolt 24 having its adjusting screw or nut 25 at the front side of the carrier, as clearly shown in Figs. 3 and 4. A 75 coiled spring 26 interposed between the carrier and said adjusting screw 25 acts to effect a yielding engagement of both the carrier and its connected shoe with the braking surfaces at opposite sides of the stationary 80 guide-plate with which they coöperate. With this arrangement and combination of parts, it will be understood that a turning of the adjusting screw 25 in the proper direction will provide a desired frictional engagement of the carrier and its shoe with the guide-plate, for properly controlling the action of the feed device in the manner and for the purpose hereinbefore referred to.

The adjusting screw 25 may be secured in 90 adjusted position by any suitable means. As here shown, I provide a self-locking means comprising a spring arm 27 secured to the carrier at 28 and at its front end having a detent 29 yieldingly engaging the adjusting 95 screw within one of a series of notches 30 therein, as shown. The yielding engagement of the detent 29 with the adjusting screw permits of the ready turning of the latter for purposes of adjustment or otherwise, and 100 the notches 30 for engagement with said detent being formed to extend lengthwise of the adjusting screw, provide for the backward and forward adjustment of the screw on the threaded stem of the bolt. 105

Referring now to Figs. 5, 6 and 7, I have here shown a slightly modified form of my invention. In this case, an adjusting screw 35 is threaded into the guide rib 21 of the carrier 9 from the rear side of the guide-plate and acts to hold the carrier and its connected shoe 23 in yielding engagement with the opposite sides of the guide-plate through a spring plate 36 interposed between the head of the adjusting screw and the shoe 23 as shown. A turning of this adjusting screw 35 operates to vary the friction between the engaging parts in substantially the same manner and for the same purpose as described with reference to the 110 construction shown in Figs. 1 to 4 inclusive. As a means for automatically locking this adjusting screw 35 in adjusted position, it is provided with a pin or detent 37 at its under side for engagement with one of a series of 115 notches 38 in the spring plate 36. An inward yielding of this spring plate disengages the same from the detent 37 and permits adjustment of the screw 35, following 120 which adjustment an outward return move- 125 130

ment of the spring automatically effects a re-locking of the adjusting screw therewith.

What I claim is:

In a machine of the class described, strip feeding means comprising a guide-plate, a carrier mounted for reciprocation on said guide-plate and supporting a pair of coöperating gripping members, means holding the carrier in frictional engagement with a 10 braking surface on the guide-plate, said means comprising an adjusting screw for varying the friction between the carrier and coöperating braking surface, and a spring

member for locking said screw in adjusted position, said spring member and the adjusting screw being provided one with a series of notches and the other with a detent engaging in said notches, for the purpose set forth.

Signed at Rochester, in the county of 20 Monroe, and State of New York, this 24th day of July A. D. 1916.

HENRY DE SMITH.
